(57) **CLAIM**

The ornamental design for a vehicle cover, as shown and described.

DESCRIPTION

A portion of the disclosure of this patent document contains material that is subject to copyright protection. The copyright owner has no objection to the facsimile reproduction by anyone of the patent document or the patent disclosure, as it appears in the Patent and Trademark Office patent files or records, but otherwise reserves all copyright rights whatsoever. The following notice applies to the disclosure herein and to the drawings that form a part of this document: Copyright 2009-2010, John Saggau, Andrew Jones, & Dave Molinari; All Rights Reserved.

This patent application is related to U.S. patent application Ser. No. 12/964,715; filed on Dec. 9, 2010; and filed by the same applicant as the present patent application.

FIG. 1 is a left side view of the vehicle cover, in accordance with a preferred embodiment of the present invention, in use on a vehicle;

FIG. 2 is a right side view of the vehicle cover, as shown in FIG. 1, in use on the vehicle;

FIG. 3 is a left side view of the forward portion of the vehicle cover, as shown in FIG. 1, in use on the vehicle;

FIG. 4 is a right side view of the forward portion of the vehicle cover, as shown in FIG. 1, in use on the vehicle;

FIG. 5 is a top side and rear view of the vehicle cover, as shown in FIG. 1, in use on the vehicle and from a view point at the rear of the vehicle;

FIG. 6 is a front view of the vehicle cover, as shown in FIG. 1, in use on the vehicle;

FIG. 7 is a top side view of the forward portion of the vehicle cover, as shown in FIG. 1, in use on the vehicle;

FIG. 8 is a front view of the lower portion of the vehicle cover, as shown in FIG. 1, in use on the vehicle;

FIG. 9 is a left side view of the vehicle cover, as shown in FIG. 1;

FIG. 10 is a top side view of the vehicle cover, as shown in FIGS. 1; and,

FIG. 11 is a bottom side view of the vehicle cover, as shown in FIG. 1.

The broken line in the drawing figures show a motorcycle and portions of a vehicle cover that form no part of the claimed design.
